CLAIM

The ornamental design for a wine glass holder, substantially as shown and described.

DESCRIPTION

FIG. 1 is a top perspective view of the wine glass holder showing my new design;

FIG. 2 is a top plan view thereof;

FIG. 3 is a front elevational view thereof, the rear elevational view being identical;

FIG. 4 is a sectional view taken along line 4—4 of FIG. 2;

FIG. 5 is a left side elevational view thereof, the right side elevational view being identical;

FIG. 6 is a sectional view taken along line 6—6 of FIG. 2;

FIG. 7 is a bottom plan view thereof.

FIG. 1**FIG. 7**

FIG. 2

FIG. 3

FIG. 4

FIG. 5

FIG. 6
